MARKING HEAD FOR A WIRE MARKING MACHINE

Ralph H. Swaisgood, Fort Collins, Colo., assignor to Storm Products Company, Los Angeles, Calif., a corporation of California

Filed Jan. 15, 1968, Ser. No. 10,167

Term of patent 14 years

Int. Cl. D15—05

U.S. Cl. D55—1

I claim:

The ornamental design for marking head for a wire marking machine, as shown.
